UNITED STATES PATENT OFFICE.

ALFRED SWENSEN, OF CICERO, ILLINOIS, ASSIGNOR TO THE CABLE COMPANY, OF CHICAGO, ILLINOIS, A CORPORATION OF ILLINOIS.

AUTOMATIC MUSICAL INSTRUMENT.

1,404,805.

Specification of Letters Patent.

Patented Jan. 31, 1922.

Application filed May 12, 1916. Serial No. 97,153.

To all whom it may concern:

Be it known that I, ALFRED SWENSEN, a citizen of the United States, residing at Morton Park, Cicero, in the county of Cook and State of Illinois, have invented new and useful Improvements in Automatic Musical Instruments, of which the following is a full, clear, concise, and exact description, reference being had to the accompanying drawing, forming a part of this specification.

My invention relates to automatic musical instruments and, more specifically, to instruments having motor-actuated air-tension-inducing devices.

Among the objects of my invention is that of providing an instrument of this type with improved means for controlling the expression.

Further objects will appear from the detailed description to follow, taken in connection with the appended claims.

In the drawings, in which one embodiment of my invention is shown.

Figure 1 is a front elevation of a player-piano embodying my invention, parts being broken away to show the interior construction;

Fig. 2 is a front elevation of the wind-chest, reservoir, feeders, and associated parts;

Fig. 3 is a plan view of the parts shown in Fig. 2;

Fig. 4 is a section, on the line 4—4 of Fig. 2;

Fig. 5 is a section, on the line 5—5 of Figs. 3 and 4;

Fig. 6 is a section, on the line 6—6 of Fig. 5;

Fig. 7 is a section of the expression-box and associated parts, on the line 7—7 of Fig. 8;

Fig. 8 is a section, on the line 8—8 of Fig. 7;

Fig. 9 is a section, on the line 9—9 of Fig. 7;

Fig. 10 is a plan view of the manually operated valve which controls the expression device;

Fig. 11 is a view, on the line 11—11 of Fig. 8;

Fig. 12 is a section, on the line 12—12 of Fig. 7;

Fig. 13 is a bottom plan view of the key-bed and parts supported thereby;

Fig. 14 is a section, on the line 14—14 of Fig. 13;

Fig. 15 is a section, on the line 15—15 of Fig. 14;

Fig. 16 is an enlarged sectional view, 60 taken on the line 16—16 of Fig. 1;

Fig. 17 is a section, on the line 17—17 of Fig. 18, showing the reroll stop;

Fig. 18 is a section, on the line 18—18 of Fig. 17; 65

Fig. 19 is a front elevation of the tracker and music-sheet;

Fig. 20 is a side view of the pump motor and the belt-tightener; and

Fig. 21 is a front view of the parts 70 shown in Fig. 20.

Referring now to the drawings in detail, the invention is shown in connection with a player-piano comprising a casing 10, any usual or suitable piano-action and pneumatic player-action, a selector-mechanism 11, which may be of any usual or suitable type, an air-motor 12 for causing the travel of the music-sheet, an expression-mechanism 13 for controlling the volume of tone, a 80 motor-operated air-tension-inducing device 14, and a foot-power air-tension-inducing device 15.

The motor-operated air-tension-inducing device comprises an air-pump 16, which may 85 be of any suitable type, and an electric motor 17 for driving the air-pump. Current is supplied to the electric motor 17 through the leading-in wires 18 and 19. The motor 17 is controlled by means of a switch 20 in circuit with the leading-in wire 19. This switch 20 is operated by means of a stem 21 which is connected to a rod 22, the end of which is located in position to be engaged by the rod 23, which is connected to the lever 24, which is pivoted at 25 to the key-bed. The end of the lever 24 is turned upwardly to form a handle 26 which can be moved back and forth in the slot 27 of the key-bed. To start the motor 17, the handle 26 is moved to the extreme right to bring the rod 23 into engagement with the rod 22 and close the switch 20. 100

For stopping the motor 17, a pneumatic 105 28 is provided, having a forked arm 29 secured to its movable leaf. This forked arm is located in position to engage the down-turned end 30 of the rod 22. The pneumatic 28 is controlled by means of a valve-action 31, which is connected with the opening 32 110

in the tracker 33 by means of the conduit 34. The valve-action 31 is connected with the pneumatic 28 by means of the conduit 35, and with the air-pump 16 by means of the 5 conduit 36, the junction-block 37 and the conduits 38 and 39. The pneumatic 28 is provided with a spring 40 which normally keeps the pneumatic expanded and holds the forked arm 29 out of operative or interfering engagement with the down-turned end 30 of the rod.

In addition to the sheet-controlled means, just described, for stopping the motor 17, a timed cut-out for the motor is provided, 15 comprising a rod 41 pivoted to the lever 24 and having a down-turned portion 42 for engagement with a push-button or cam-member 43 secured on the rod 44, a valve 45 located in position to be operated by the 20 rod 44, a conduit 46 controlled by the valve 45, a valve-action 47 connected with the conduit 46 and controlling the slow-acting pneumatic 48, a restricted conduit 49 connecting the valve-action 47 and the slow- 25 acting pneumatic 48, a spring-valve 50 located in position to be engaged by the finger 51 secured to the movable leaf of the pneumatic 48, and a conduit 52 controlled by the spring valve 50 and connected to the 30 valve-action 31 which controls the pneumatic 28.

No claim is made in this application to the timed cut-out, just described.

For operating the reroll and tempo-indicator mechanism, a rod 53 is provided, connecting the lever 24 with a rock-shaft 54 which is connected to suitable reversing and indicating mechanism. The reversing mechanism (not illustrated, as it may be of any 35 suitable type) controls the direction of rotation of the music-spool 55 and of the take-up roll 55^a. This take-up roll 55^a is provided with a hook 55^b for detachably engaging the ring 55^c of the music-sheet 78. To prevent 40 accidental reversing of the travel of the music-sheet, a movable stop 56 is located in position to be engaged by the lever 24. This stop is mounted on a spring-support 57 (Fig. 44), and its movement is limited by means of 45 a screw 58 embedded in the key-bed. The end of the stop 56 is provided with an abutment 59 for engaging the lever 24. The stop 56 is recessed at 60 to receive the lever 24 when the stop is moved down so that the 50 abutment 59 clears the lever 24. For automatically moving the abutment 59 out of the way of the lever 24 at the end of the forward travel of the music-sheet a pneumatic 61 is provided, having an arm 62 which extends 55 within the recess 63 in the stop 56. This pneumatic 61 is connected by means of a conduit 64 with a valve-action 65, which valve-action also controls the pneumatic 66 which operates the reroll and action-cut-off mechanism. This pneumatic 66 is provided with a

finger 67 on its movable leaf, which engages the down-turned end 68 of the action-cut-off rod 23, to which is secured the valve-rod 68^a of the action-cut-off valve. The pneumatic 66 is provided with a spring 69 for holding it 70 in expanded position. The valve-action 65 is connected with the opening 70 in the tracker by means of the conduit 71. For stopping the music-spool 55 as soon as the music-sheet uncovers the opening 70, in rewinding, a 75 pneumatic 72 is provided, having a hook-arm 73 secured to its movable leaf for engagement with the hook-arm 74 secured to rotate with the spindle 75 supporting the music-spool 55. The pneumatic 72 is connected, by 80 means of the tube 76, with the valve-action 31 which controls the motor-stop-pneumatic 28.

The action of the parts thus far described is as follows: To start the electric motor 17, 85 the lever 24 is moved to the extreme causing the rod 23 to engage the rod 22 and close the switch 20. The lever 24 is then positioned to give the desired speed to the air-motor 12, or is manipulated to give any desired speed to the music-sheet. After the selection has been played, a perforation 77 in the music-sheet 78 registers with the opening 70 in the tracker, admitting air through the conduit 71 to the valve-action 65. This results in the collapse of the pneumatics 61 and 66. The pneumatic 61 will act under lower tension and therefore acts before the pneumatic 66. As the pneumatic 61 collapses, it moves the abutment 59 out of the path of the lever 100 24. As the pneumatic 66 collapses, the finger 67 engages the down-turned end 68 of the rod 23 and moves the lever 24 over until it enters the recess 60 in the stop 56. The movement of the lever 24 to this position will 105 reverse the connections between the air-motor 12 and the music-spool 55 and take-up roll 55^a to cause the music-sheet to be rewound. At the same time, the rod 23 cuts off pneumatic communication of the player-action with the wind-chest 86 by movement of the valve-rod 68^a to close the attached action-cut-off valve. The complete, or nearly complete, rewinding of the music-sheet exposes the opening 32 in the tracker. The air is 110 thus admitted through the conduit 34, to the valve-action 31, causing the pneumatics 28 and 72 to collapse, opening the switch 20 to stop the motor 17 and throwing the hook-arm 73 into the path of the hook-arm 74 to 115 stop the music-spool 55 from rotating, thus preventing the free end of the music-sheet 78 from flapping.

In order to effect the shutting off of the electric current and the stopping of the motor 17, should the lever 24 be left for a considerable length of time in zero position, the timed cut-out for the motor 17 is provided, as described above. The action of the timed cut-out is, briefly, as follows: If the lever 24 120

is moved to a position in which it engages the abutment 59, the tempo-indicator will be in zero position and pneumatic communication of the air-motor 12 with the wind-sheet will be completely cut off, so that the air-motor will stop. When the lever 24 engages the abutment 59, the down-turned portion 42 of the rod 41 engages the push-button 43, causing the rod 44 to open the valve 45. Opening of the valve 45 admits air through the conduit 46, to the valve-action 47, causing the pneumatic 48 to slowly collapse. When the pneumatic 48 is nearly collapsed, the finger 51 engages the spring-valve 50 and opens it, admitting air to the conduit 52, thus causing the operation of the valve-action 31, the collapse of the pneumatic 28, and the opening of the switch 20 whenever the lever 24 is allowed to remain in the just-described position long enough for the slow-acting pneumatic 48 to reach and open the spring-valve 50.

For controlling the speed of the air-motor 12, the down-turned portion 42 of the rod 41 is connected to the valve rod or stem 79 which is connected to the tempo-valve 80 (Fig. 5). The tempo-valve 80 controls the port 81 which affords communication between the air-motor 12 and the regulated-air passage 82 of the wind-chest 86, the air-pressure in the passage 82 being controlled by means of the regulator 83 which may be of any usual or suitable construction.

For obtaining high speed of the air-motor 12, a high-tension valve 84 is provided, controlling the port 85 which affords direct communication between the air-motor and the wind-chest 86. This high-tension valve 84 is located in position to be opened by the tempo-valve 80, when the latter is moved to the extreme right (Fig. 5). In order to prevent injuriously high tension in the air-motor 12, a relief-valve 87 is provided, which controls an atmospheric port 87a. This relief-valve 87 is mounted on a spring-support 88 fulcrumed about a screw 89. The tension of the spring-support 88 is regulated by means of a screw 90. The air-motor 12 is in communication with the valve-box 90a through the conduit 91. The wind-chest 86 is in communication with a collapsible reservoir 92 through the port 93 (Fig. 4). When the motor-operated air-tension-inducing device 14 is being used, it is desirable that the reservoir 92 be cut off from the wind-chest 86, or at least that the communication between the wind-chest and reservoir be restricted. For this purpose a valve 94 is provided for the port 93, and a pneumatic 95 is provided for controlling this valve. A rod or stem 95a is connected to the movable leaf of the pneumatic 95, and extends, through an opening, in the wall of the reservoir 92, into engagement with the valve 94. The pneumatic 95 is in free communication with the exhaust from the air-pump through the conduit 96. A spring 97 acts to close the valve 94 when the pneumatic 95 collapses. A spring 98 acts on the pneumatic 95 to expand the latter and open the valve when the motor-operated air-tension-inducing device 14 is not running. In order that the reservoir 92 may act to help out the device 14, when necessary, the valve 94 may be provided with a restricted opening 99, which is so small that the flow of air therethrough to the wind-chest 86, due to an increase in the air-tension in the wind-chest, does not materially modify the air-tension in the wind-chest, but permits a restricted flow to equalize the tension in the reservoir and wind-chest. As the tension in the reservoir tends to become the same as that in the wind-chest, it follows that, if the tension in the wind-chest is suddenly reduced, as on account of a large number of notes being simultaneously sounded, the reservoir will expand, due to the action of the spring, the valve 94 will be sucked open against the pressure of the spring 97, and the reservoir 92 will draw in air from the wind-chest 86 to help out the motor-operated device 14. The wind-chest 86 is in communication with the air-pump 16 through the conduit 100, past the check-valve 101, through the conduit 102, junction-block 103, conduit 104, junction-block 37, and conduits 38 and 39.

The operation of the parts just described is as follows: The tempo-valve 80 can be placed in any desired position, with respect to the port 81, to give any desired speed to the air-motor 12, by means of the lever 24. When the lever 24 is moved to "rewind" position, i. e., the position which reverses the connections to cause rewind of the music sheet, the tempo-valve 80 engages the high-tension valve 84 and opens the port 85, thus connecting the air-motor directly with the wind-chest 86. If the tension in the wind-chest 86 becomes excessive, the relief-valve 87 will open against the pressure of the spring-support 88 to relieve the tension and prevent undue strain upon the air-motor. This relief-valve 87 is particularly useful when the air-motor 12 is suddenly stopped, due to the hook-arm 74 engaging the hook-arm 73.

The expression-mechanism 13, for controlling and graduating the volume of tone by causing various degrees of air-tension to apply in the action wind-chest through variations of the admission of atmospheric air, may be controlled either by the music-sheet or manually. This device (as shown in detail in Figs. 7, 8, 9, 10, 11, and 12) comprises an expression-box 105; a muffler 106, through which atmospheric air enters to the expression-box; and primary valve-mechanism 107, the valve-actions 107a, 107b, 107c, and 107d of which are respectively connected

with the openings 108, 109, 110, and 111 of the tracker through the conduits 112, 113, 114, and 115, junction-block 116, and conduits 117, 118, 119, and 120.

5 The expression-box 105 comprises an air-chamber 121, having an atmospheric inlet-port 122 controlled by a yielding spring-pressed valve 123, and an air-chamber 124, in communication with the air-chamber 121 through the ports 125, 126, 127, 128, and 129. The ports 126, 127, 128, and 129 are controlled, respectively, by means of valve-mechanisms 130, 131, 132, and 133 which, in turn, are controlled, respectively, from the primary valve-actions 107^a, 107^b, 107^c, and 107^d. The valve 123 is mounted on a spring-support 135, fulcrumed on a screw 136. For adjusting the tension of the spring-support 135, it is provided with a downwardly extending arm 137, having an opening through which extends a rod or stem 138 having a threaded portion engaging a nut 139, which nut is held from rotation by engagement with the wall of the air-chamber 121. A thumb-wheel or button 140 is secured to the outer end of the stem 138 for rotating it. To prevent fluttering or vibration, the valve 123 is connected, by means of a rod 141, to a check pneumatic 142 having a restricted opening 143, through which the air is forced in and out as the check-pneumatic is moved by the movement of the valve 123. This check-pneumatic forms, in effect, a dash-pot for preventing vibration of the valve 123.

35 The valve-mechanisms 130, 131, 132, and 133 are alike and the description of one will suffice. Each comprises a valve-disc 144 cooperating with the corresponding valve-seat 145, a valve-stem 146 slideable in 40 the guide 147, and a diaphragm or pouch 148 for operating the valve. These pouches 148 extend over the air-chambers 149, 150, 151, and 152, which are connected with the valve-actions 107^a, 107^b, 107^c, and 107^d, respectively, through the conduits 153, 154, 155, and 156. The air-chamber 149 is in communication with the air-chamber 150 through the passage 158^a; the air-chamber 150 is in communication with the air-chamber 151 through the passage 156^b; and the air-chamber 151 is in communication with the air-chamber 152 through the passage 156^c. The air-chamber 150, 151, and 152 are provided with flap check-valves 157, controlling the passages 156^a, 156^b, and 156^c, respectively, and with flap check-valves 158, controlling the conduits 154, 155, and 156, respectively. Each of the flap check-valves 158 is provided with a vent or bleed 159 to 55 permit the air to be exhausted from beneath the diaphragm 148. The air-chamber for the valve-actions 107^a, 107^b, 107^c, and 107^d is in communication with the air-chamber 124, through a conduit 161 (Fig. 7). The air-chamber 124 is connected with the air-pump

16, through the port 134, conduit 160, junction-block 103, conduit 104, junction-block 37, and conduits 38 and 39. For regulating the flow of air through the ports 126, 127, and 128, regulating-valves 162, 163, and 164 are provided, which regulating-valves may be simply capstan-screws extending into the ports and adjustable to vary the effective port-opening.

5 The port 125 is provided with a yielding pressure-operated valve-mechanism, constituting a high-tension relief valve and comprising a valve 165, hinged at 166 and pressed against its seat by means of a spring-bell-crank 167, which is mounted in 80 bearings 168 and has a downwardly extending arm 169, through which extends the stem 170, which has a threaded portion engaging the wing-nut 170^a and a thumb-wheel or button 170^b for rotating the stem. 85 The wings of the wing-nut 170^a are located so that they will straddle the downwardly extending arm 169 and be prevented from moving when the stem 170 is rotated. For preventing fluttering or vibration of the valve 165, a check-pneumatic 171 is provided, bearing on the lower surface of the valve. This check-pneumatic has a restricted opening 171^a, through which air is forced as the check-pneumatic is expanded and collapsed, and is provided with a spring 171^b for holding it against the lower surface of the valve 165. This check-pneumatic 171 acts as a dash-pot to prevent vibration of the valve 165. The muffler 106, through 90 which atmospheric air passes to the expression-box 105 comprises a chest 172, open at the top to admit the air, and a plurality of baffle-walls 173 located within the chest, forming a tortuous passage 174 for the air 95 to the expression-box.

For manually controlling the expression mechanism 13 the junction-block 116 (Fig. 10) is provided with ports 175, 176, 177, and 178, in communication with the conduits 117, 118, 119, and 120, respectively, and these ports are controlled by means of a slide-valve 179 which is connected, by means of the valve-rod 180, with the hand-lever 181 (Fig. 1) which operates in the recess 182 in 115 the key-bed. The music-sheet 78 is provided with suitable perforations 183, 184, 185, and 186 for registration with the respective openings 108, 109, 110, and 111, for controlling the valve-mechanisms 130, 131, 132, 120 and 133, respectively, to obtain the various degrees of air-tension in the action wind-chest. The music-sheet is also provided with the usual note-perforations 187 for controlling the action-pneumatics. The expression-mechanism 13 controls the air-tension in the conduits 160, 104, and 102, and in the wind-chest 86, by variably restricting the communication of the conduit 160 with the atmosphere. All the air which enters 125 130

the conduit 160 is taken through the muffler 106 and through the inlet-port 122, past the yielding spring-pressed valve 123, into the air-chamber 121. From the air-chamber 121, however, the flow of air to the conduit 160 may be either through the port 125 alone or through port 126, or through the two ports 126 and 127, or through the three ports 126, 127, and 128, or through all four of the ports 126, 127, 128, and 129, depending on the manner in which the music-sheet is perforated or the position in which the slide-valve 179 (Fig. 10) is held.

Describing first the sheet-control and 15 regarding the manual control, if it is desired that a passage of music be played "pp," no perforations will be provided in the music-sheet for any of the tracker-openings 108, 109, 110, and 111, and air can flow into 20 the conduit 160 through all four of the ports 126, 127, 128, and 129. If it is desired that the passage be played p, the music-sheet is provided with a perforation, or series of perforations, 186 for registration with the 25 tracker-opening 111 to admit air to the conduit 120 for controlling the valve-action 107^d and cause the actuation of the valve-mechanism 133 to close the port 129. With the parts in this position, the flow of air to the 30 conduit 160 will be through the three ports 126, 127, and 128, which will cause an increase in the tension in the wind-chest 86 and a corresponding increase in the volume of tone. If it is desired to play a passage 35 mf, the music sheet is provided with a perforation, or series of perforations, 185 for registration with the tracker-opening 110, to admit air to the conduit 119 for controlling the valve-action 107^c, and thus admit air to 40 the air-chamber 151, and through the passage 156^c, to the air-chamber 152, causing both valve-mechanisms 132 and 133 to close their respective ports 128 and 129. With the parts in this position, the flow of air 45 to the conduit 160 is restricted to the ports 126 and 127, causing a corresponding increase in the tension in the wind-chest 86. If it is desired to play a passage f, the music-sheet is provided with a perforation, or 50 series of perforations, 184 for registration with the tracker-opening 109. This will cause the admission of air to the air-chamber 150 and, through the passages 156^b and 156^c, to the air-chambers 151 and 152, causing 55 all three of the valve-mechanisms 131, 132, and 133 to be closed and the flow of air to the conduit 160 to be restricted to the flow through the port 126. If it is desired to play a passage ff, the music-sheet 60 is provided with a perforation, or series of perforations, 183 for registration with the tracker-opening 108, which will cause admission of air to the air-chamber 149 and also, through the passages 156^a, 156^b, and 65 156^c, to the air-chambers 150, 151, and 152,

causing all four of the valve-mechanisms 130, 131, 132, and 133 to be closed and the flow of air to the conduit 160 to be restricted to that which flows through the port 125 alone, thus giving the highest degree of 70 tension in the wind-chest.

The different grades of expression can be regulated by adjustment of valve 123 and by means of the regulating-valves 162, 163, and 164, which can be set to give the 75 degrees of tension which it is desired the opening and closing of the valve-mechanisms 130, 131, 132, and 133 shall obtain. The valve 165 can also be adjusted by means of the button 170^b to determine the maximum tension. By making the tracker-openings 108, 109, 110, and 111 elongated, transversely of the tracker (as shown in Fig. 19), the perforations of the music-sheet which control these openings can be spaced some 85 distance apart and still permit a continuous flow of air to the said openings, so that the music-sheet is not weakened to the extent that it would be if the perforations were closer together. It will be noted that the 90 openings in the tracker which cause the higher degrees of tension in the wind-chest are located farther from the edge of the sheet, so that the danger of sounding a note, or notes, under marked increase of tension, 95 through a defective sheet, is less than it would be in a tracker in which the openings causing the higher degrees of tension were located nearer the edge of the sheet.

If it is desired to control the expression 100 manually, the slide-valve 179 is moved to uncover any desired number of the ports 178, 177, 176, and 175, and thus effect the closing of any desired number of the valve-mechanisms 133, 132, 131, and 130. In order to cause positive actuation of the 105 reroll pneumatics 61 and 66 the music-sheet 78 is provided with a perforation 183, which will register with the tracker-opening 108 when the perforation 77 registers with the 110 reroll opening 70 in the tracker. This causes the application of high tension in the wind-chest when the reroll pneumatics 61 and 66 are actuated, thus causing these 115 pneumatics to act promptly and reliably. It will be noted that there are no perforations in the music-sheet for registration with the motor-stop opening 32 in the tracker, as this opening 32 is flushed only when the music-sheet leaves the tracker, as, 120 for instance, when the music-sheet has been completely rewound. As a consequence of the fact that the music-sheet has no perforation for registration with the opening 32, there are no perforations in the music-sheet which will travel anywhere near the reroll opening 70 in the tracker so that 125 there is no danger of accidental actuation of the reroll mechanism.

In Fig. 16 is shown a mechanism for pro- 130

ducing a mandolin effect. This mechanism comprises a bar 188, extending across in front of the strings and mounted on an arm 189 which is pivoted at 190 to any suitable support. A plurality of flaps 191 are secured to the bar 188, and each flap has a weighted lower end 192 which is vibrated against the string 192^a when the flap 191 is struck by the piano-hammer 192^b, causing a mandolin effect. The bar 188 is movable from the full-line position (shown in Fig. 16), in which the flaps 191 are above the piano-hammers, to the dotted-line position shown, in which the flaps lie between the piano-hammers and the strings. For moving the bar 188, a pneumatic 193 is provided, which is secured to the roll-box 194 by means of a bracket 195. This pneumatic 193 is controlled by means of a valve-action 196, which is connected with the pneumatic 193 by means of a conduit 197, with the tracker-opening 198 by means of a conduit 198^a, and with the action wind-chest by means of a conduit 199. A bent arm 200 is secured to the movable leaf of the pneumatic 193 and has a down-turned portion 201, which engages the bar 188 to move it from the full-line position to the dotted-line position.

To permit easy manual operation of the pneumatic 193, it is provided with a flap check-valve 202, which controls the port 203 so that, when the pneumatic 193 is manually collapsed, the air can easily escape therefrom through the port 203 and past the check-valve 202. This check-valve 202 is located in a position to be engaged by the down-turned portion 201 of the arm 200, to insure that the check-valve 202 will be in its proper position, closing the port 203, when the valve-action 196 acts to cause the pneumatic 193 to be exhausted. A spring 204 is provided for returning the arm 189 and bar 188 from the dotted-line position to the full-line position.

For manually operating the bar 188, a combined operating and latching member 205 is connected to the movable leaf of the pneumatic 193 by means of a lost-motion connection 206, which permits the collapse of the pneumatic without corresponding movement of the operating member. This operating member 205 has a laterally bent portion 207 which operates in a slot 208 in the frame of the roll-box 194. This slot 208 has an off-set portion 209, with which the laterally bent portion 207 of the member 205 engages to latch the pneumatic 193 in collapsed position and hold the bar 188 and flaps 191 in operative position.

The positioning of the mandolin-rail is accomplished as follows: If it is desired to have the device operate automatically the music-sheet 78 is provided with a perfora-

tion, or series of perforations, 210 for registration with the tracker-opening 198, to cause air to be admitted to the conduit 198^a and control the valve-action 196 to cause the collapse of the pneumatic 193, which will bring the flaps 191 to a position between the hammer-pianos 192^b and the strings 192^a. If it is desired to operate the mandolin-rail manually, the member 205 is pushed in, and the portion 207 is brought into engagement with the off-set portion 209 of the slot 208, causing the flaps 191 to move to a position between the piano-hammers and strings. The tracker 33 is provided with the usual opening 211 for controlling the dampers for the piano-action.

In order that the belt 212, which transmits power from the motor 17 to the air-pump 16, shall be maintained at the proper tension, a belt-tensioning device is provided. To this end, the rear legs 213 of the motor 17 rest on a support 214 in such a manner that the front end of the motor can tilt about this support 214 as an axis, the front end of the motor being supported solely by the belt 212. In order to vary the tension in the belt 212 in accordance with the power required from it a pneumatic 215 is provided, which is in communication with the air-pump 16 through the conduit 216, junction-block 37, and conduits 38 and 39. This pneumatic is connected by means of a link 217 with a cross-bar 218 which, in turn, is connected to the front legs 219 of the motor 17. For supporting the front end of the motor in case the belt 212 should break, a U-shaped support 220 is located in position to be engaged by the front legs 219 of the motor, should the front end of the motor drop down. The pneumatic 215 is also secured to this support.

The operation of this belt-tensioning device is as follows: The power required of the motor 17 will be proportional to the air-tension in the air-pump 16, and the downward pull of the pneumatic 215 on the motor 17 will also be proportional to the air-tension in the air-pump. This downward pull of the pneumatic 215 is transmitted to the belt 212 so that the tension in the belt 212 will be proportional to the power required of the motor 17.

Having thus described my invention, what I claim as new and desire to secure by Letters Patent is:—

1. An expression - device for automatic musical instruments of the exhaust type, comprising a chamber provided with outlet-means for communicating with the exhaust, a second chamber provided with inlet-means for communicating with the atmosphere, a yielding pressure-operated valve controlling said inlet-means, port-means affording communication between said chambers,

valve-means controlling said port-means and means for varying the effective area of said port-means.

2. An expression-device for automatic musical instruments of the exhaust type, comprising a chamber provided with outlet-means for communicating with the exhaust, a second chamber provided with inlet-means for communicating with the atmosphere, a yielding pressure-operated valve controlling said inlet-means, a plurality of ports affording communication between said chambers, and means for closing one of said ports.

3. An expression-device for automatic musical instruments of the exhaust type, comprising a chamber provided with outlet-means for communicating with the exhaust, a second chamber provided with inlet-means for communicating with the atmosphere, a yielding pressure-operated valve controlling said inlet-means, a plurality of ports affording communication between said chambers, valves for controlling some of said ports, and pneumatics for actuating said valves.

4. An expression-device for automatic musical instruments of the exhaust type, comprising a chamber provided with outlet-means for communicating with the exhaust, a second chamber provided with inlet-means for communicating with the atmosphere, a yielding pressure-operated valve controlling said inlet-means, a plurality of ports affording communication between said chambers, valves for controlling some of said ports, pneumatics for actuating said valves, means affording communication between some of said pneumatics, and a check-valve controlling said communication means.

5. An expression-device for automatic musical instruments of the exhaust type, comprising a chamber provided with outlet-means for communicating with the exhaust, a second chamber provided with inlet-means for communicating with the atmosphere, a yielding pressure-operated valve controlling said inlet-means, a plurality of ports affording communication between said chambers, valves for controlling some of said ports, and sheet-controlled means for actuating said valves.

6. An automatic sheet-controlled musical instrument of the exhaust type, comprising an expression-device having a chamber provided with outlet-means for communicating with the exhaust, a second chamber provided with inlet-means for communicating with the atmosphere, a pressure-operated valve controlling said inlet-means, a plurality of ports affording communication between said chambers, and sheet-controlled valves for controlling some of said ports.

7. An expression-device for automatic musical instruments of the exhaust type, comprising a chamber provided with outlet-

means for communicating with the exhaust, a second chamber provided with inlet-means for communicating with the atmosphere, a yielding pressure-operated valve controlling said inlet-means, a plurality of ports affording communication between said chambers, valves for controlling some of said ports, and manually controlled means for selectively controlling said valves.

8. An expression-device for automatic musical instruments of the exhaust type, comprising a chamber provided with outlet-means for communicating with the exhaust, a second chamber provided with inlet-means for communicating with the atmosphere, a yielding pressure-operated valve controlling said inlet-means, a plurality of ports affording communication between said chambers, valves for controlling some of said ports, pneumatics for actuating said valves, and manually controlled means for selectively controlling said pneumatics.

9. An expression-device for automatic musical instruments of the exhaust type, comprising a chamber provided with outlet-means for communicating with the exhaust, a second chamber provided with inlet-means for communicating with the atmosphere, a yielding pressure-operated valve controlling said inlet-means, a plurality of ports affording communication between said chambers, valves for controlling some of said ports, pneumatics for actuating said valves, means affording communication between some of said pneumatics, a check-valve controlling said communication means, a plurality of ports in communication with said pneumatics, and a slide-valve for successively controlling the last said ports.

10. An expression-device for automatic musical instruments of the exhaust type, having an atmospheric inlet port, a pressure-operated spring-pressed valve controlling said inlet-port, and a dash-pot for modifying the action of said valve.

11. An expression-device for automatic musical instruments of the exhaust type, having an atmospheric inlet-port, a pressure-operated spring-pressed valve controlling said inlet-port, and a bellows for modifying the action of said valve and actuated thereby, said bellows having a restricted opening through which air is forced as said bellows is actuated.

12. An automatic musical instrument comprising a manually operated air-pump and a motor-operated air-pump, a wind-chest in communication with both said air-pumps, a yielding pressure-controlled reservoir in communication with said wind-chest, and means, operable upon said operation of the motor-operated air-pump, but not operable upon the operation of said manually operated air-pump, for obstructing the collapse of said reservoir.

13. An automatic musical instrument comprising a manually operated air-pump and a motor-operated air-pump, a wind-chest in communication with both said air-pumps, a yielding pressure-controlled reservoir in communication with said wind-chest, and means, operable upon the operation of said motor-operated air-pump but not operable upon the operation of said manually operated air-pump for obstructing the collapse of said reservoir, said means including a pneumatic in communication with said motor-operated air-pump.
14. An automatic musical instrument comprising a manually operated air-pump and a motor-operated air-pump, a wind-chest in communication with both said air-pumps, a yielding pressure-controlled reservoir, a port through which said reservoir communicates with said wind-chest, and means, operable upon the operation of said motor-operated air-pump, but not operable upon the operation of said manually operated air-pump, for obstructing said port.
15. An automatic musical instrument comprising a manually operated air-pump and a motor-operated air-pump, a wind-chest in communication with both said air-pumps, a yielding pressure-controlled reservoir, a port through which said reservoir communicates with said wind-chest, and a pneumatic in communication with said motor-operated air-pump for controlling said port.
16. An air-controlling device for automatic musical instruments, comprising an air-chamber having a port, a yielding pressure-operated valve for controlling said port, and means for preventing fluttering and vibration of said valve comprising a dash-pot acting on said valve.
17. An air-controlling device for automatic musical instruments, comprising an air-chamber having a port, a yielding pressure-operated valve for controlling said port, and means for preventing fluttering and vibration of said valve comprising a dash-pot acting on said valve; said dash-pot comprising a bellows having a restricted opening, through which air is forced due to the movement of said valve.
18. An expression-device for automatic musical instruments of the exhaust type, comprising a chamber provided with outlet-means for communicating with the exhaust, a second chamber provided with inlet-means for communicating with the atmosphere, a yielding pressure-operated valve controlling said inlet-means, port-means affording communication between said chambers, means for varying the effective area of said port-means, and means for preventing vibration of said pressure-operated valve comprising a dash-pot.
19. An expression-device for automatic musical instruments of the exhaust type, comprising a chamber provided with outlet-means for communicating with the exhaust, a second chamber provided with inlet-means for communicating with the atmosphere, a yielding pressure-operated valve controlling said inlet-means, port-means affording communication between said chambers, means for varying the effective area of said port-means, and means for preventing vibration of said pressure-operated valve comprising a dash-pot; said dash-pot comprising a bellows having a restricted opening, through which air is forced due to the movement of said valve.
20. An expression-device for automatic musical instruments of the exhaust type, comprising a chamber provided with outlet-means for communicating with the exhaust, a second chamber provided with inlet-means for communicating with the atmosphere, a yielding pressure-operated valve controlling said inlet-means, a plurality of ports affording communication between said chambers, means for closing one of said ports, a yielding pressure-operated valve controlling another of said ports, and means for preventing vibration of the last said valve comprising a dash-pot.
21. An expression-device for automatic musical instruments of the exhaust type, comprising a chamber provided with outlet-means for communicating with the exhaust, a second chamber provided with inlet-means for communicating with the atmosphere, a yielding pressure-operated valve controlling said inlet-means, a plurality of ports affording communication between said chambers, means for closing one of said ports, a yielding pressure-operated valve controlling another of said ports, and means for preventing vibration of said valves comprising dash-pots acting on said valves.
22. An automatic musical instrument comprising a wind-chest, a manually operated air-pump in communication with said wind-chest, a power-driven air-pump also in communication with said wind-chest, a reservoir, a port affording communication between said wind-chest and said reservoir, a check-valve controlling said port, a pneumatic in communication with said power-driven air-pump controlling said check-valve, and a restricted port affording communication between said reservoir and said wind-chest.
23. An automatic musical instrument comprising a wind-chest, a manually operated air-pump in communication with said wind-chest, a power-driven air-pump also in communication with said wind-chest, a reservoir, a port affording communication between said wind-chest and said reservoir, a check-valve controlling said port, a pneumatic in communication with said power-driven air-pump controlling said check-valve.

valve, said check-valve having a restricted port therein affording communication between said reservoir and said wind-chest.

24. An expression-device for automatic musical instruments of the exhaust type, comprising a chamber provided with outlet-means for communicating with the exhaust, a second chamber provided with inlet-means for communicating with the atmosphere, a yielding pressure-operated valve controlling said inlet-means, a plurality of ports affording communication between said chambers, valves for controlling some of said ports, and manually controlled means for progressively controlling said valves.

25. A collapsible and expandible air-reservoir having a moving board and a check mounted to be moved into and away from a position to restrict the motion of said moving board, a shiftable element independent of said moving board, and a shifting-means connected to said shiftable element and to a moving part of said check.

26. A collapsible and expandible air-reservoir having a moving board, air-pumper-means and foot-pedals for their operation, air-pumper-means and power-means for

their operation, and a movable check mounted to be moved to and away from a position to restrict operation of the said moving board during the operation of said power-operated air-pumper means.

27. A collapsible and expandible air-reservoir having a moving board, foot-operable air-pumper-means and power-operable air-pumper-means, and a movable check mounted to be moved into and away from a position to restrict the operation of said moving board during the operation of said power-operable air-pumper-means.

28. An expression-device for automatic musical instruments of the exhaust type, said device comprising a chamber provided with outlet-means for communicating with the exhaust, a second chamber provided with inlet-means for communicating with the atmosphere, a valve yieldingly resisting the entrance of atmospheric air through said inlet-means, port-means affording communication between said chambers, and means for controlling said port-means.

In witness whereof, I have hereunto subscribed my name.

ALFRED SWENSEN.
